GAME APPARATUS

Paul John McElhaney, 2185 Estabrook Circle,
San Leandro, Calif.
Filed June 3, 1960, Ser. No. 33,865
1 Claim. (Cl. 273—37)

My invention relates to a game apparatus embodying a new game of skill, to be known as Polo Ten-Pins, which will consist of ten small maple pins, a large maple mallet, and an ebonite ball.

The object of this invention is to provide a new and interesting game requiring much less playing area than either bowling or croquet, while being readily adaptable to both indoor and outdoor use—an approved hardwood floor will be required for tournament play, but, for convenience, the game may be played on almost any type of surface.

The accompanying drawings will illustrate the size and construction of the playing area, as well as the equipment necessary for this new and different game.

FIGURE 1 is a plan view of the playing area; FIGURE 2 is a cross section view of the Alley and Player's Platform; FIGURE 3 is a side view of the playing area; FIGURE 4 is a side view of the maple mallet and ball; and FIGURE 5 is a side view of the maple pin and ball.

FIGURE 1, the plan view of the playing area, consists of the Pit (A), the Alley (B), and the Player's Platform (C).

The Pit is an area forty four inches wide, by forty eight inches long; it surrounds the end of the Alley, on which the pins are spotted. The Pit area is surrounded on the sides and back by a curb 14 with a cotton filled canvas matting 15, for the protection of the pins and balls; the curb is twenty inches in height. Both the floor of the pit A and the inner surfaces of the curb 14 are padded to deaden the sound, when the pins 22 strike the padding.

The Alley is a maple surfaced area, twenty eight inches wide and twenty one feet three inches long. The Alley has a curbing 13 of one inch plywood, ten inches in height, that is firmly secured to both sides of the Alley; the curb extends from the Player's Platform to the curb 14 of the Pit area. Ten maple pins 22 are spotted on a twenty two inch triangle at the end of the Alley.

The Player's Platform is of the same maple surfaced material as the Alley; it is forty two inches long, and sixty four inches wide. The Platform has a painted foul line, which is twenty feet from the head pin; the ball 21 is played between two diamond shaped markers in back of the foul line.

FIGURE 2 is a cross section showing the construction of the Alley. In the Alley and Player's Platform redwood runners 10 are firmly secured to the floor or ground; the runners are to be surfaced, and must be three inches high and not less than four inches wide. A one inch plywood subsurface 11 is firmly secured to the runners. A maple planking 12 is then applied to the subsurface; the planking must be not less than five sixteenths of an inch thick, and not more than two inches in width; it is finished by sanding and lacquering. A one inch plywood curb 13 is firmly secured to both sides of the Alley.

FIGURE 3 is a side view of the elevation of the entire playing area, showing: the twenty inch curb 14 of the Pit area, the ten inch curb 13 of the Alley, the pins 22 spotted on a twenty two inch triangle at the end of the Alley, and the Player's Platform; the ball 21 is played from the foul line, twenty feet from the head pin.

FIGURE 4 shows a side elevational view of the maple mallet. The mallet head 16 is turned from solid maple;

2

it is two and five eighths inches in diameter, and eight and one half inches in length, tapering slightly at the ends; firm rubber or plastic tips 18 of three eighths inch thickness are cemented firmly to the ends of the mallet head 16. The handle, also of maple 19 is one inch in diameter and twenty six and one half inches in length; it is threaded two inches into the center of the mallet head. The grip area 20 is fourteen inches long, and, for a slip free grip, is covered with spiral wrapped perforated leather. The ball 21 is of polished ebonite, four inches in diameter, weighing exactly thirty two ounces.

FIGURE 5 is a vertical section of the maple pin 22 which is turned from solid maple; it is eight and one half inches in height, one and five eighths inches at the base, and three inches at its widest point.

The game will be played by spotting the ten pins on a twenty two inch triangle at the end of the Alley; the pins will be numbered from one through ten. The ball 21 will be driven from the Player's Platform back of the foul line, which is twenty feet from the head pin. Each player will have ten turns or frames, playing two balls per frame; the scoring will be the same as in bowling.

I claim:

In a game apparatus: a player's platform; an elongated alley extending forwardly from the player's platform; the alley having an upper surface disposed flush with an upper surface of the player's platform, whereby a ball resting on the player's platform may be propelled by a mallet so as to roll along the alley; the alley having a forward end provided with a pin-spotting area on which a plurality of pins may be placed for striking by the ball, when the latter is rolled forwardly; a pit disposed at the forward end of the alley, and having the pin-spotting area located within the pit; the pit having spaced side curbs located laterally beyond the lateral sides of the alley, and further having a back curb spaced longitudinally beyond the forward end of the alley, whereby the pit extends around two sides and one end of the pin-spotting area to receive the ball and struck pins; a pair of spaced side curbs extending lengthwise of the alley from the players' platform up to but not beyond that end of the pit which is nearer the player's platform, whereby the struck pins may be deflected laterally from the pin-spotting area of the alley and against the side curbs of the pit, the side curbs of said alley being of less height than the side curbs of said pit, the side curbs of the alley being butted against the adjacent lateral sides of the alley, whereby the ball will be confined to the upper surface of the alley as it rolls forwardly therealong; the player's platform extending transversely relative to the length of the alley and projecting beyond both lateral sides of the alley, whereby a player may stand on either laterally-projecting portion of the player's platform; the player's platform having a foul line on its upper surface extending transversely relative to the length of the alley to indicate a location back of which the player must stand; the upper surface of the player's platform further being provided with a pair of spaced markers adjacent to the foul line and indicating an area in which the ball must be placed prior to being struck by the mallet.
